UNITED STATES PATENT OFFICE.

ALBERT AUGUSTUS MOSS, OF NEWARK, NEW JERSEY.

CAR-COUPING.

SPECIFICATION forming part of Letters Patent No. 758,268, dated April 26, 1904.

Application filed November 30, 1903. Serial No. 183,218. (No model.)

To all whom it may concern:

Be it known that I, ALBERT AUGUSTUS MOSS, a citizen of the United States, residing at Newark, in the county of Essex and State of New Jersey, have invented a new and useful Car-Coupler, of which the following is a specification.

This invention relates to car-couplers of that general class shown in United States Letters Patent granted to me on the 2d day of July, 1901, under No. 677,366.

The object of the invention is to improve, simplify, and strengthen the construction of this class of couplers and to provide means for automatically locking the pivoted jaw in its closed or coupled position and means for opening said jaw when the lock is released.

A further object of the invention is to provide means for retaining the lock in its inoperative position and to provide a flexible connection between the pivoted jaw and the locking means, so that when said jaw is swung outwardly it will automatically release the locking means, causing the latter to stand in the path of the pivoted jaw and in a position to automatically engage and lock said jaw as the same is closed.

A still further object is to provide a common operating-lever for setting and releasing the locking-dog and for automatically opening the pivoted jaw after said dog has been released.

With these and other objects in view the invention consists in the construction and novel combination and arrangement of parts hereinafter fully described, illustrated in the accompanying drawings, and pointed out in the claims hereto appended, it being understood that various changes in form, proportion, and minor details of construction may be resorted to without departing from the principle or sacrificing any of the advantages of this invention.

In the accompanying drawings, Figure 1 is a perspective view of a car-coupler constructed in accordance with the present invention. Fig. 2 is a transverse horizontal sectional view of the same. Fig. 3 is a vertical sectional view taken on the line 3-3 of Fig. 2.

Fig. 4 is a detail perspective view of the locking pin or dog detached. Fig. 5 is a detail sectional view showing the position of the locking-pin when set or in the inoperative position.

Similar numerals of reference indicate corresponding parts in all the figures of the drawings.

1 designates the draw-head, having the usual recess or chamber 2 and oppositely-disposed fixed jaws 3 and 4, the fixed jaw 3 being bifurcated, as shown at 5, for the reception of the pivoted jaw or coupling-knuckle 6. The side wall of the recess or chamber 2 opposite the fixed jaw 4 is provided with a longitudinal strengthening-rib 7, which extends from the shank or draw-bar 8 to the front end of said chamber, the terminal portion of the rib being concaved, as shown at 9, to permit free pivotal action of the jaw or knuckle 6 when coupling or uncoupling. The jaw or knuckle 6 comprises the outer and inner angularly-related arms 10 and 11, the arm 11 of which is bifurcated to form a pair of spaced parallel arms 12 and 13, said arms being provided with aligned openings 14 for the reception of a coupling-pin when the draw-head is connected to an ordinary link-and-pin coupler. The arms 12 and 13 are formed with terminal hooks 15, adapted to engage a vertically-disposed rib or shoulder 16 on the side wall of the chamber 2 when the knuckle 6 is closed, the bifurcation in the knuckle permitting the latter to clear the rib 7 as said jaw or knuckle is swung inwardly.

The rear side of the arm 13 of the pivoted knuckle 6 is cut away to form an inclined shoulder or cam-flange 16^a, which inclines upwardly and forwardly from the hook 15 to a point adjacent the center of said arm and serves to engage and actuate a locking cam or dog 16^b when the knuckle is closed, as will be more fully explained hereinafter. The locking cam or dog 16^b is pivotally mounted on a vertical pin 17, located opposite the inner arm of the knuckle 6 and is provided with a lateral projection 18 and a vertically-disposed locking-lip 19, adapted to engage coincident notches or shoulders 20 in the parallel arms

12 and 13 of the knuckle 6 when said knuckle is closed, thereby securely locking the same in the closed position.

Arranged within the chamber 2 at a point 5 adjacent the cam or dog and preferably cast integral with the draw-head is an inclined rib or track 21, upon which the dog or cam 16^b travels when a rearward pull is exerted on the latter, causing said dog in its upward 10 movement to make a partial rotation and engage and lock the pivoted knuckle, as will be readily understood. The rib or track 21 is provided with a rearwardly-inclined shoulder 22, (shown in dotted lines in Fig. 5,) adapted 15 to form a seat or rest for the dog 16^b and retain the same out of operative relation with the pivoted knuckle when desired, said shoulder also forming a means for setting the locking cam or dog, as will be more fully explained hereinafter.

The base of the dog 16^b is provided with a tapering recess 22', the inclination of which corresponds to the inclination of the shoulder 22, so that when the dog is resting on the 25 shoulder said dog is prevented from being accidentally displaced by any sudden jar or movement of the cars incident to coupling or uncoupling.

A recess 23 is formed in the upper arm 12 30 of the pivoted knuckle 6, and secured therein in any suitable manner, as by a staple 24, is a chain or other flexible medium 25, the opposite end of which is fastened to a similar staple 26, preferably secured to the lip 19 of the 35 locking dog or cam, so that when the dog or cam is set or resting on the shoulder 22 and the knuckle 6 opened it will release the dog and cause it to drop in a position to engage and automatically lock the knuckle when the cars 40 are again coupled.

As a means for opening the pivoted knuckle 6 I provide a lever 27, one end of which is pivoted between a pair of upwardly-extending lugs or ears 28, preferably formed integral with the draw-head, the opposite end of 45 the lever extending in the path of the pivoted knuckle and engaging a shoulder or recess 29 in the end of the arm 12. Secured to the lever 27 is one end of a chain or cable 30, the 50 opposite end of which passes through an opening 31 in the draw-head and over a roller or clevis 31', secured in any suitable manner to the crank-arm of a hand-operated shaft 32, journaled in suitable bearings on the car-body, so that when the lock is released and an upward 55 pull is exerted on the cord or chain it will cause the lever 27 to engage the knuckle and swing the same open. One end of a link 33 is pivoted in a recess 33' in the locking cam 60 or dog 16^b, the opposite end thereof being secured to the chain 30, so that by operating the shaft 32 the lock may be set or caused to engage the shoulder 22 of the inclined rib or track.

65 In some cases the locking-shoulder 22 may

be dispensed with, the dog being held and positively locked in the elevated position by means of a toothed cone 32' on the lever 32, which engages a correspondingly-shaped bearing 32² when the lever 32 is moved longitudinally, said lever permitting the dog to drop as soon as the cone 32' is withdrawn from its bearing, as will be readily understood.

The arms 12 and 13 of the pivoted knuckle 6 are provided with upwardly-projecting lugs 75 34, which fit in correspondingly-shaped grooves or recesses 35, formed in the upper and lower walls of the chamber 2 when the knuckle 6 is closed and engage lugs or ears 35' on the fixed jaw 3 when said knuckle is 80 open and serve to relieve the pivot-pin of a portion of the strain incident to coupling or uncoupling and drawing the cars.

The knuckle 6 is recessed, as shown at 35², to accommodate the lugs or ears 35', said lugs 85 engaging the inner wall of the recesses when the knuckle is closed, as clearly shown in Fig. 2 of the drawings.

In order to permit free lateral movement of the draw-head in traveling around curves, I 90 provide a pair of centering-springs 36, mounted one on each side of the shank 8, said springs being housed in suitable boxes 38, secured to the draft-timber or other portion of the car.

From the foregoing description the construction of my device will be readily understood, and the operation thereof may be briefly described as follows: The coupler being in the locked position, the shaft 32 is operated to pull upwardly on the chain or cable, whereby 100 the dog or cam is swung upwardly and rearwardly by traveling over the inclined rib or track 21 until it engages the shoulder 22, when the dog or cam will be set. When the dog or cam is in this position, the vertical lip 105 19 thereof will be disengaged from the knuckle and a further movement of the shaft 32 will cause the lever 27 to force the pivoted jaw open, said jaw pulling on the chain 25 in its outward movement, releasing the dog or 110 cam and causing it to drop to the bottom of the chamber 2 and in a position to automatically engage and lock the jaw when the coupling is again operated. When two couplers are brought together, each knuckle is forced 115 inwardly, whereby the cam-flange 16^a engages beneath the projection 18 of the locking-dog, swinging the latter rearwardly and also elevating the same until the knuckle swings clear of the dog, when the latter will automatically 120 swing into its normal position and in locked engagement with the free end of the knuckle.

It will be observed by having the shoulder 22 on the inclined track the dog or cam is held out of engagement with the knuckle, 125 permitting the lever 27 to open the same, the forward or outward movement of the jaw automatically returning the dog to its normal position.

If desired, the chain 25, instead of being 130

secured to the lip 19 of the locking-dog, may be fastened in any suitable manner to the rear side thereof, and any well-known form of ratchet-lever may be employed for operating the shaft 32.

Having thus described the invention, what is claimed is—

1. In a car-coupler of the class described, the combination of a draw-head having a recess or chamber, of a pivoted angular knuckle, one end of which is adapted to swing into and out of said recess, a vertically-sliding dog pivoted within the chamber or recess and provided with a locking-lip adapted to engage the knuckle, and a flexible connection between the knuckle and the locking-lip of said dog.

2. In a car-coupler of the class described, the combination of a draw-head having a recess or chamber provided with a vertically-disposed rib, of a pivoted angular knuckle having terminal hooks adapted to engage said rib, a vertically-sliding locking-dog pivoted within the recess and adapted to engage the knuckle, means for setting the locking-dog, means for opening the knuckle and a flexible connection between the rear end of the knuckle and the locking-dog.

3. In a car-coupler of the class described, the combination of a draw-head having a recess or chamber provided with an inclined track, of a pivoted angular knuckle, one end of which is adapted to swing into and out of said recess, a locking-dog pivoted within the recess and slidable on the track for engagement with the knuckle, an inclined shoulder on the track for holding the locking-dog out of engagement with the knuckle and a flexible connection between said knuckle and locking-dog.

4. In a car-coupler of the class described, the combination of a draw-head having a recess or chamber, a pivoted angular knuckle, one end of which is adapted to swing into and out of said recess, a vertically-sliding dog pivoted within the recess and provided with a locking-lip adapted to engage the knuckle, a kicking device for opening the knuckle, a flexible connection between the knuckle and the locking-lip of the dog and a single lever for setting said sliding dog and operating the kicking device.

5. In a car-coupler of the class described the combination of a draw-head having a recess or chamber provided with a longitudinal strengthening-rib and a laterally-disposed projection, a pivoted angular knuckle adapted to swing into and out of said recess, said knuckle being provided with terminal hooks adapted to engage the lateral projection, a vertically-sliding locking-dog pivoted within the recess and adapted to engage the knuckle, means for setting the locking-dog, and a flexible connection between the locking-dog and the knuckle.

6. In a car-coupler of the class described, the combination of a draw-head having a re-

cess or chamber, of a pivoted angular knuckle provided with coincident notches or recesses adapted to swing into and out of said recess or chamber, a vertically-sliding locking-dog pivoted within the recess and adapted to engage the notches in the knuckle for locking the same in the closed position, means for throwing the locking-dog out of engagement with the knuckle, means for opening the knuckle, and a flexible connection between the knuckle and the locking-dog.

7. In a car-coupler of the class described, the combination with a draw-head having a recess or chamber the upper and lower walls of which are grooved or recessed, of a pivoted angular knuckle, provided with oppositely-disposed lugs adapted to engage said grooves, a vertically-sliding locking-dog pivoted within the recess and adapted to engage the knuckle, means for holding the locking-dog out of operable relation with the knuckle and means for automatically resetting said dog when the knuckle is opened.

8. In a car-coupler of the class described, the combination with a draw-head having a recess or chamber, of a pivoted angular knuckle, one end of which is bifurcated to form a pair of hooked arms adapted to swing into and out of said recess, a cam-flange formed on one of said arms; a rearwardly-swinging and vertically-sliding locking-dog pivoted in the recess and having its free end in locking relation to said arms, a projection on the dog arranged in the path of the cam-flange and adapted to engage the same for elevating the dog, means for holding the dog out of operable relation with the knuckle and a flexible connection between the dog and the knuckle for automatically resetting the former when the latter is opened.

9. In a coupler of the class described, the combination with a draw-head having a recess or chamber, the upper and lower walls of which are grooved or recessed, a pivoted angular knuckle provided with oppositely-disposed lugs adapted to engage said grooves, a vertically-sliding locking-dog pivoted within the recess and adapted to engage the knuckle, means for releasing the locking-dog, and means for opening the knuckle.

10. In a coupler of the class described, the combination with a draw-head having a recess or chamber, of a pivoted angular knuckle, provided with coincident notches or recesses, a vertically-sliding dog pivoted in the recess and provided with a locking-lip adapted to engage the notches in said knuckle, means for releasing and opening the knuckle and a pair of centering-springs mounted in housings, one on each side of the draw-head.

11. In a car-coupler of the class described, the combination with a draw-head having a recess or chamber provided with strengthening-ribs, a pivoted angular knuckle, one end of which is adapted to swing into and out of said

recess, a locking-dog pivoted within the recess, a lock-set, a kicking device, an operating-lever having a roller-clevis secured thereto, and a flexible connection passing over the 5 clevis and connecting the locking-dog and the kicking device.

12. In a car-coupler of the class described, the combination with a draw-head having a recess or chamber, a pivoted angular knuckle 10 having its front portion solid and its bifurcated rear portion provided with aligned openings and adapted to swing into and out of said recess, there being a vertically-disposed opening formed in the draw-head adapted to receive a locking-pin for connecting the draw-head to a link-and-pin coupler.

13. In a car-coupler of the class described, the combination with a draw-head having a recess or chamber and provided with oppositely- 20 disposed fixed jaws, ears or lugs formed on one of the fixed jaws, and an angular knuckle pivoted to said fixed jaw and provided with corresponding ears or lugs adapted to engage the lugs thereon for limiting the outward 25 movement of the knuckle, said knuckle being provided with grooves or recesses adapted to receive the lugs on the fixed jaw for limiting the inward movement of said knuckle.

14. In a car-coupler of the class described, 30 the combination with a draw-head having a re-

cess or chamber, a pivoted angular knuckle provided with terminal coincident notches or recesses, a vertically-sliding dog pivoted within the chamber or recess and provided with a locking-lip adapted to engage the notches in 35 the knuckle, eyelets riveted to the knuckle and to locking-lip of the dog, respectively, a flexible connection between said eyelets, a socket formed in the locking-dog, a link seated within the socket for operating the dog, 40 and a pin or rivet passing through the socket and engaging the link.

15. In a car-coupler of the class described, the combination with a draw-head having a recess or chamber provided with a vertically- 45 disposed rib, ears or lugs on one of the fixed jaws, an angular knuckle pivoted to the draw-head and provided with corresponding ears or lugs for engagement with the lugs on the fixed jaw, said knuckle being provided with terminal hooks adapted to engage the rib when the knuckle is closed.

In testimony that I claim the foregoing as my own I have hereto affixed my signature in the presence of two witnesses.

ALBERT AUGUSTUS MOSS.
